ASH TRAY

Frederick W. Grantham, Winnetka, Ill.

Application September 6, 1938, Serial No. 228,467

8 Claims. (Cl. 131—240)

The invention relates to improvements in ash trays adapted for smokers' use and has for its primary object the provision of an improved ash tray so constructed and arranged as to discharge automatically a cigarette or the like placed thereon to prevent the falling of said cigarette therefrom due to continued burning, which is of simple construction and highly efficient in use.

Another object of the invention is the provision of an improved ash tray of the character indicated so constructed and arranged as to insure operation thereof under various conditions of use.

Other objects will appear hereinafter.

The invention consists in the combinations and arrangements of parts hereinafter described and claimed.

The invention will be best understood by reference to the accompanying drawing forming a part of this specification and in which

Fig. 1 is a top plan view of an ash tray embodying the invention;

Fig. 2 a vertical transverse section of the same taken substantially on line 2—2 of Fig. 1;

Fig. 3 an enlarged partial view illustrating the positions of parts assumed in operation; and

Fig. 4 a section taken substantially on line 4—4 of Fig. 2.

The embodiment of the invention illustrated in the drawing comprises a receptacle 10 having a raised bottom 11 arranged to support burning cigarettes or cigars discharged into said receptacle in such a manner as to prevent damage from heat to an underlying supporting surface such as a highly finished table top. The receptacle 10 is provided with a removable cover member 12 having an inwardly tapering conical mouth 13 providing a central entry opening 14 through which ashes, cigarettes and cigar stubs may be inserted into the receptacle 10.

Brackets 15 are secured as shown at diametrically opposite points of the under side of the mouth 13 and are provided with depending perforated supporting ears 16 for pivotally supporting two trap doors 17 on pivot pins 18 supported between the ears 16, as shown. Each trap door 17 is provided with a counterweight 19 normally holding the same in closed position but permitting of downward yielding thereof to permit the insertion of ashes and stubs into the receptacle 10, as will be readily understood. Supporting brackets 20 are secured as shown to diametrically opposite points of the top side of the mouth 13 directly above the brackets 15 and are provided as shown with upwardly and inwardly ex-

tending perforated supporting ears. Pivotally mounted on each of the brackets 20 is a cigarette or cigar support 22 having depending perforated ears 23 pivotally supported on a supporting pin 24 extending between the ears on the supporting bracket 20, as shown. A helical coil 25 of thermostatic metal is arranged as shown on each pivot pin 24, one end 26 of said coil being given a turn around the corresponding pin 24 and extended through the bottom of the corresponding bracket 20 and the mouth 13 to anchor the same in place, as shown. The other end 27 of the coil 25 is given a turn around the pivot pin 24 and extended outwardly and substantially horizontally so as to make contact with the under side of the corresponding support 22 when elevated a short distance. A flexible chain 28 is connected with the outer end of each arm 27 and with the under side of the corresponding trap door 17, there being a loop 29 formed in each chain so as to provide for slight lost motion between the end of the arm 27 and the corresponding trap door. The coil 25 of thermostatic material is formed of two adjacent strips of metal welded together and having different coefficients of expansion so that heat applied to the coil 25 causes unwinding of said coil and consequent swinging of the arm or end 27 thereof. Each support 22 carries a stop arm 30 normally resting under the end 27 of the corresponding coil 25, as best shown in Fig. 2. Each support 22 is provided with a central opening 31 affording access of heat from a supported cigarette or cigar stub to the underlying thermostatic coil 25. As shown, a sharp edge 32 is provided at the inner end of each opening 31 and a protective and reinforcing lip 33 is provided at the inner end of each support 22.

When a cigarette or cigar is laid upon one of the supports 22 and continues to burn, as soon as the heat thereof reaches the thermostatic coil 25, said coil automatically operates to cause upward and inward swinging of the end 27 thereof. Initial movement of said arm 27 will bring the same into contact with the under side of the corresponding support 22 thus tilting said support upwardly and inwardly. After such upward and inward tilting has proceeded long enough to move the center of gravity of the said cigarette or cigar stub materially inwardly, the lost motion in chain 28 will be taken up and upward tension exerted on the outer end of the corresponding trap door 17, thereby tilting the body of said trap door downwardly to open the same. Continued burning of the supported cigarette or cigar stub will continue this motion and opera-

tion until the support 22 passes the vertical through its pivot, whereupon it will suddenly topple inwardly, thus completely and positively discharging the supported cigarette or cigar stub. As indicated in Fig. 3, the arm 30 on the support 22 striking against the outer side of the end 27 limits such inward movement. The arrangement is such that when a cigarette stub is laid upon one of the supports 22 as indicated by the dotted lines at the left of Fig. 2, continued burning thereof causes an ash to form which rests upon the sharp edge 32, said sharp edge 32, in effect, "digging" into said ash to engage it sufficiently to hold the burning cigarette from sliding during the upward tilting of the support so that the operation thereof will be positively continued and the cigarette stub positively discharged at the end of the operation as explained above. Likewise, if a cigarette stub is placed further out on the support so as to bring the lighted end or ash into direct contact with the coil 25, the end of the ash contacts directly with the edge 32 during the upward tilting of the support, thereby preventing sliding of the stub and compelling complete and positive discharge thereof at the end of the motion, as before. Thus in any position in which a lighted stub is placed upon one of the supports 22, continued burning thereof will automatically effect positive and complete discharge thereof into the ash receptacle. As soon as the lighted stub is thus discharged into the receptacle, the coil 25 starts to cool and, as it cools, the operating end 27 is withdrawn and returned to original position, thereby returning the support 22 to its original position and releasing the corresponding trap door 17 so that it may return to its original closed position under the influence of its weight 19, thus automatically restoring the parts for reoperation.

In this way, when a lighted cigarette or cigar stub is laid upon one of the supports 22, and forgotten by the smoker, its continued burning will cause its automatic, positive, and complete discharge into the ash tray, and will thereby prevent its toppling outwardly onto the supporting surface of the ash tray when its consumption has continued long enough to cause the protruding outer end to outweigh the consumed inner end thereof. Thus the highly polished surface of table tops upon which the ash trays may rest will be automatically and perfectly protected from accidental burning and marring by cigarette or cigar stubs toppling from the supports onto said table tops. The specific form and arrangement of parts disclosed is a simple and effective one for the purpose.

While I have illustrated and described the preferred form of construction for carrying the invention into effect, this is capable of variation and modification without departing from the spirit of the invention. I therefore do not wish to be limited to the precise details disclosed, but desire to avail myself of such variations and modifications as fall within the scope of the appended claims.

I claim:

1. An ash tray comprising an ash receptacle; a support mounted thereon and arranged to operate to discharge thereinto; thermostatic means

for operating said support; said support having means for retaining an article thereon in fixed relation thereto until the same has completely operated.

5. 2. An ash tray comprising an ash receptacle; a support mounted thereon and arranged to operate to discharge thereinto; thermostatic means for operating said support; said support having rest means located above the thermostatic means

10 and spaced therefrom in a direction toward the center of the tray for retaining an article on and in fixed relation to said support until the same has completely operated.

3. An ash tray comprising an ash receptacle; a support mounted thereon and arranged to operate to discharge thereinto; thermostatic means for operating said support; said support having a sharp edge located above the thermostatic means

20 and spaced therefrom in a direction toward the center of the tray for retaining an article on and in fixed relation to said support until the same has completely operated.

4. An ash tray comprising an ash receptacle; a support pivotally mounted thereon and arranged to tilt beyond the vertical through its pivot to discharge thereinto; thermostatic means for tilting said support to a position beyond the vertical and then releasing it; and means on said support for retaining an article thereon until the same has completely tilted.

5. An ash tray comprising an ash receptacle; a support pivotally mounted thereon and arranged to tilt beyond the vertical through its pivot to discharge thereinto; thermostatic means for tilting said support to a position beyond the vertical and then releasing it; said support having rest means located above the thermostatic means

30 and spaced therefrom in a direction toward the center of the tray for retaining an article on and in fixed relation to said support until the same has completely operated.

6. An ash tray comprising an ash receptacle; a support pivotally mounted thereon and arranged to tilt beyond the vertical through its pivot to discharge thereinto; thermostatic means for tilting said support to a position beyond the vertical and then releasing it; said support having a sharp edge located above the thermostatic means and spaced therefrom in a direction toward the center of the tray for retaining an article on and in fixed relation to said support until the same has completely operated.

7. An ash tray comprising an ash receptacle; a support pivotally mounted thereon and arranged to tilt beyond the vertical through its pivot to discharge thereinto; and thermostatic means for tilting said support to a position beyond the vertical and then releasing it.

8. An ash tray comprising an ash receptacle; a support pivotally mounted thereon and arranged to tilt upwardly and inwardly beyond the vertical through its pivot to discharge thereinto; a thermostatic coil having one end anchored to said receptacle and the other end arranged to contact with the under side of said support to tilt the same; and an arm on said support passing under said other end of said thermostatic coil, whereby said support when it passes the vertical through its pivot will be free to topple inwardly to discharge an article thereon.

FREDERICK W. GRANTHAM.
